UNITED STATES PATENT OFFICE

CHARLES F. DYSERT, OF JOHNSTOWN, PENNSYLVANIA

AEROPLANE KITE

Application filed October 7, 1929. Serial No. 397,966.

This invention relates to kites, the primary object of the invention being to provide a kite which will fly in the usual and well known manner, and one which will have the 5 appearance of an aeroplane in action.

An important object of the invention is to construct a kite of transparent material such as glassine or the like and form the outline of an aeroplane on the underside of 10 the kite, the outline of the aeroplane and that portion of the kite between the lines of the outline of the aeroplane being opaque, causing the outline of the aeroplane to stand out against the sky.

15 With the foregoing and other objects in view, which will appear as the description proceeds, the invention resides in the combination and arrangement of parts and in the details of construction hereinafter described

20 and claimed, it being understood that changes in the precise embodiment of the invention herein disclosed, may be made within the scope of what is claimed, without departing from the spirit of the invention.

25 Referring to the drawings:

Figure 1 is a bottom plan view of a kite constructed in accordance with the invention.

30 Figure 2 is an end elevational view thereof.

Referring to the drawings in detail, the kite embodies the usual frame comprising a longitudinal member 5 and a transverse member 6, to which the body portion 7 of the 35 kite is secured.

40 This body portion 7 is formed of transparent material such as glassine or the like so that light rays from the sky will be projected therethrough and will be invisible to the eye of a person observing the kite from the ground surface, while the kite is flying.

45 The body of the kite is curved in the usual and well known manner, the outer and inner surfaces thereof being supplied with a heavy line 8 outlining the body and wings of an aeroplane, the portion between the lines forming the outline of the aeroplane being coated with a material to cause the body portion within the outline to be opaque, with 50 the result that the kite while flying, will

simulate in appearance and actions, an aeroplane.

It will of course be understood that the body portion of the aeroplane may be cut out of opaque material and pasted or otherwise secured to the body of the kite to lend the appearance of an aeroplane.

55 The usual kite string is secured to the body portion of the kite and the kite is flown in the well known manner.

I claim:

60 In a kite, a transparent body portion completely transparent to the eye, an opaque member outlining a figure, secured to the body portion, and said opaque portion being outlined by a heavy opaque line.

65 In testimony that I claim the foregoing as my own, I have hereto affixed my signature.

70 CHARLES F. DYSERT.
